PHELAN McSHANE, OF PITTSBURGH, PENNSYLVANIA, ASSIGNOR TO WESTINGHOUSE ELECTRIC & MANUFACTURING COMPANY, A CORPORATION OF PENNSYLVANIA

MANIPULATOR PUSHER HEAD

Application filed August 13, 1927. Serial No. 212,619.

This invention relates generally to control systems and more particularly to control systems for manipulator pusher heads for rolling mills.

5 The object of the invention, generally stated, is the provision of a control system which shall be simple and efficient in operation, readily and economically manufactured and installed and in which provision for 10 proving the operation of this type of machine is made by reducing the abusive action imposed upon the motor.

A more specific object of the invention is to provide for utilizing the counter electro- 15 motive force developed in a motor to control the variation of resistance in the motor circuit, to assure that sufficient resistance is connected in series with the motor to protect it when it is stalled by the jamming of the 20 pusher head.

Another object of the invention is to provide for the connecting of a resistor in series with a pusher head actuating motor after it has been accelerated and before it is stalled 25 by the jamming of the pusher head.

Other objects of the invention will become evident from the following detailed description taken in conjunction with the accompanying drawing, in which:

30 Figure 1 is a view in end elevation of a steel rolling mill of a type suitable for the application of the present control system.

Fig. 2 is a diagrammatic view of the main and auxiliary circuits of a control system 35 connected in accordance with the invention.

Referring now to Fig. 1 of the drawing, the structure here shown comprises a well-known type of rolling mill, provided with a roll table 5 having the usual stands or end 40 supports 6 for the table rollers 7. As shown, the rollers are actuated by the bevel gear arrangement 8 which may be driven in any suitable manner (not shown).

In order to position stock such as ingots or 45 billets, etc., on the table, a pusher head 9 and the required actuating mechanism 11 is provided. As shown, the pusher head 9 is carried by a horizontal beam 12 which is operated by means of a rack and pinion drive 50 comprising members 14 and 15. The move-

ment of the pusher head is in a plane parallel to the top of the table 5, from the full open position as shown to the full closed position near the opposite side of the roll table 5. As is the usual practice, an electric motor 16 55 is utilized for operating the rack and pinion drive. In this instance a reduction gear train 17 is interposed between the motor 16 and pinion 15.

Mounted opposite to the pusher head 9 is 60 a similar mechanism 18. This member 18 is a part of a second manipulator pusher head mechanism similar to 11, and is disposed to be actuated in like manner and can either function to move the ingot or billet 21 in a 65 transverse path across the rolls or as a stop in case the billet is being moved by the opposite disposed pusher head 9.

A cam switch 22, here shown connected to the reduction gear train 17, is provided for 70 the purpose of limiting the travel of the pusher head in either the forward or reverse directions and to control various other control circuits in a manner which will be described hereinafter.

75 Referring to Fig. 2, the system shown comprises a pusher head actuating motor 16 having a series field winding 23. The cam switch 22 is shown as geared directly to the motor shaft, although it is to be understood that this switch may also be operated from any shaft contained within the gear case 17 or from any shaft which bears a definite relation to the position of the pusher head.

80 As will be noted, the cam switch 22 comprises a plurality of cam members 24 to 27, inclusive, mounted upon a common shaft and disposed to operate a plurality of switches 28 to 31, inclusive. The gear arrangement which drives the cam shaft is 85 designed to effect one complete revolution of the cams as the pusher head travels from the open to the closed position, or vice versa, the purpose being to complete at a predetermined time certain control circuits which will be 90 described hereinafter.

95 In the control system a plurality of reversing switches 32 to 35, inclusive, are provided and disposed to be employed to reverse the armature connections of the motor 16. 100

A dynamic braking contactor 36 is also provided to establish a dynamic braking circuit for the motor 16 at the full open position of the pusher head. In addition, the operation 5 of the contactor 36 effects the operation of a main contactor 37 which, as will be observed, is connected in series relation to the resistor 38 and series field winding 23 and constitutes a means of effecting a final connection of the 10 motor to the negative power conductor 39 after the proper reversing contactors have established the armature connections. It will be readily understood then that the main contactor 37 is governed in its operation by 15 the dynamic braking contactor 36, insuring that dynamic braking connections will only be established when the motor has been entirely disconnected from the power source.

A master switch 41 having a plurality of 20 fixed contact fingers 42 to 45, inclusive, which are disposed to be bridged by the movable segment 46, is provided for controlling the operation of the reversing contactors 32 to 35, inclusive, and to establish various other control 25 circuits which will be described hereinafter.

Assuming that it is desired to effect the 30 forward operation of the pusher head, the master switch 41 is actuated to the forward position, bridging the stationary contact members 42 and 43 with the movable contact segment 46, which establishes an operating circuit for the reversing contactors 32 and 33, which extends from the positive conductor 47, conductor 48, contact member 42, conductor 35 49, cam switch contact member 28, which is closed, conductor 51, coil 52 of the reversing contactor 33, conductor 53, coil 54 of the contactor 32, conductor 55 to the negative conductor 39.

40 It will also be noted that upon the operation of the master controller 41 a second energizing circuit is established to effect the operation of a contactor 56, and which extends from the positive conductor 47, conductor 48, master switch contact member 42, conductor 49, limit switch contact member 28, conductors 51 and 57, coil 58 of contactor 56, conductors 59, 61 and 55 to the negative conductor 39.

50 In this instance the contact members of relay 56 are connected in parallel relation to the cam operated contact members 31 which stand open when the pusher head is in its full open position, insuring that a control circuit for effecting the forward operation of the pusher head can always be obtained regardless of the position of the cam switch.

The closure of contactor 56 establishes a 55 circuit which extends from the positive conductor 47, conductor 62, the closed contact member of contactor 56, conductor 63, operating coil 64 of the dynamic braking contactor 36 to the negative conductor 39. This affects the operation of the dynamic braking contactor 36 which opens contact members

65 and 66 and closes contact member 67, thereby interrupting a dynamic braking circuit which will be referred to hereinafter, and completes an operating circuit for the main contactor 37 which was partially established 70 by the master controller 41 and which extends from the positive conductor 47, through conductor 48, master controller contact member 43, conductor 68, contact member 67, conductor 69, coil 71 of the main contactor 37, 75 to the negative conductor 39.

The closure of the main contactor 37 closes the main motor circuit which was partially established by the operation of the reversing contactors 32 and 33 and which extend from the positive conductor 47, through conductors 72 and 73, contact member 74 of the reversing contactor 32, conductors 75 and 76 to the motor terminal designated as 77, through the armature winding, terminal 78, conductors 79 and 81, switch 33, conductor 82, series field winding 23, conductor 83, series resistor 38, main contactor 37 to the negative conductor 39.

In accelerating the motor 16 provision is 90 made for short-circuiting a portion of the resistor 38. In order that the acceleration may be automatically controlled when the motor is started, a relay 84 which is responsive to the counter electromotive force developed in the motor is provided for controlling the actuating circuit of relay 85 which is disposed to short-circuit a portion of the resistor 38.

When the motor is started, the actuating 100 coil of the relay 84 is subjected to a voltage since it is directly connected across the armature. It is well understood that the counter-electromotive force of direct current motor is developed gradually as the motor starts 105 from rest and is accelerated to full speed.

The actuating coil of the relay 84 which is disposed to respond to a low value of counter-electromotive force voltage and may be energized sufficiently to effect the operation 110 of the relay and thus close the contact members 86 which are normally biased to their open positions by means of the spring 87.

The closure of contact members 86 establishes an energizing circuit for the short-circuiting contactor 85, which extends from the positive conductor 47, through conductors 62 and 88, contact members 86 of the counter electromotive force relay 84, conductor 89, contact member 91 of relay 92, conductor 93, coil 94 of short-circuiting contactor 85, to the negative conductor 39.

The closure of the short-circuiting contactor 85 thereby short-circuits a portion of the resistor 38 and the motor 16 accelerates to 125 full speed.

At this point in the cycle of operation the pusher head 9 is being actuated toward the closed position to move any billet that may be carried by rolls. At a predetermined po- 130

sition the movement of the billet will be suddenly stopped by the oppositely disposed pusher head 18, thus causing the actuating motor 16 to be stalled. Unless provision has been made for limiting the current drawn by the actuating motor, before jamming of the pusher head 13 occurs, said current will rise to an excessive and dangerous value in the motor circuit which would, unless interrupted quickly, have a destructive effect upon the motor windings.

In order to protect the motor, provision is made for connecting a resistor in series with it. Therefore, before the jamming of the pusher head occurs, a resistor 38 is connected in the motor circuit.

It will be noted that a second relay 92 was utilized in establishing the energizing circuit for the short-circuiting contactor 85.

The relay 92 is provided with an operating coil 95 which is also connected directly across the motor terminals, and is, therefore, disposed to be energized by the counter-electromotive force of the motor. When the actuating motor 16 has reached approximately full speed and the developed counter-electromotive force has reached such a value as to effect the operation of the relay 92, thus opening the contact members 91 which were biased to the closed position by means of the spring 96.

Upon the operation of the relay 92 the energizing circuit of the short-circuiting contactor 85 is interrupted and it drops open, thereby inserting the total amount of the resistor 38 in the motor circuit before the motor is stalled.

It will readily be seen that the amount of time occurring between the starting and stalling of the motor 16 is sufficient for the relay 92 to function in the manner described hereinbefore, thus insuring that a current limiting resistor is in the motor circuit, which resistor has little effect until the motor is suddenly stalled.

The counter-electromotive force relays 84 and 92, when functioning in the proper manner, utilize a common resistor 38 for the purpose of accelerating the motor and for automatically protecting the motor when it is stalled.

After the motor is stalled, the operator either returns the controller to the "off" position or to the "reverse" position to either maintain the pusher head 9 in engagement with a billet or to return it to the full open position.

Assuming that the pusher head is to be returned to the full open position, then the controller 41 is actuated to the "reverse" position, which action effects the bridging of contact members 44 and 45 of the master controller 41 by the movable segment 46 and establishes an operating circuit for the reversing contactors 34 and 35, which are disposed

to reverse the armature connections of the motor 16, thus establishing a power circuit of opposite polarity, which reverses the direction of rotation of the motor 16.

The operating circuit for the contactors 34 and 35 thus established extends from the positive conductor 47, conductor 48, stationary contact member 45 of the master controller 41, conductor 97, limit switch contact members 29 which are now in engagement, conductor 98, where a parallel circuit is established, one branch extending through conductor 99, coil 101 of the contactor 35, conductor 55 to the negative conductor 39. The other branch extends from energized conductor 98 through conductor 102, coil 103 of the contactor 34, conductors 61 and 55 to the negative conductor 39.

In this instance the limit switch contact members 31 are in engagement having been closed by the cam member 27 immediately after the pusher head 9 is moved from the full open position as described hereinbefore.

Therefore the operating circuit for the dynamic braking contactor 36 which was energized before the reversing occurred, remains energized, thus the contact members 67 of the contactor 36 are maintained in the closed position.

As mentioned hereinbefore, the operating circuit for the main contactor 37 may be established only when the contact members 67 of the relay 36 are in engagement. Therefore, upon the actuation of the master controller 41 to the reverse position, the operating circuit for the main contactor 37 is established, which extends from the positive conductor 47, through conductor 48, the movable segment 46 and contact finger 44, conductor 68, the closed contact members 67 of the contactor 36, conductor 69, coil 71 of the main contactor 37 to the negative conductor 39.

Thus, the reversing contactors 34 and 35 and the main contactor 37 are closed simultaneously, which establishes the main motor circuit extending from the positive conductor 47, through conductor 72, contactor 34, conductor 79, armature terminals 78 and 77, conductors 76, 105 and 106, contactor 35, series field winding 23, conductor 83, resistor 38, main contactor 37 to the negative conductor 39. The motor 16 operates in the reverse direction with the full amount of resistor 38 in the circuit.

The counter-electromotive force relays 84 and 92 again function in the manner described hereinbefore to short-circuit a portion of the resistor 38, thus quickly accelerating the motor to the full speed and again inserting the full amount of resistance in series with the motor after it has reached full speed in the reverse direction.

When the pusher head is nearing the full open position, it is desirable to slow the mo-

tor down to some extent, therefore, at a point near the full open position of the pusher head, the cam switch contact members 30 are closed by the action of the cam 26 which establishes an energizing circuit for the armature shunt slow down contactor 108, which, upon the closure of its contact members 114 connects the resistor 109 in shunt relation to the armature of the motor 16. This armature shunt slow-down circuit extends from terminal 77, of the motor 16, through conductors 76 and 105, resistor 109, conductor 110, the closed contact members 111 of reversing contactor 82, which is now deenergized, conductor 112, contactor 108, conductors 113 and 79 to the terminal 78 of the motor 16.

In this manner the speed of the motor is reduced automatically as the pusher head nears the full open position. At the full open position the cam switch contacts 30 are again opened, which deenergizes the armature shunt slow-down contactor 108 and interrupts the armature shunt circuit.

25 In this embodiment of the invention to provide for quickly stopping the pusher head in the full open position, dynamic braking is resorted to. Therefore, a dynamic braking circuit is established by reason of the 30 fact that the cam switch 31 has opened and deenergized the operating coil 64 of the dynamic braking contactor 36, permitting contact members 65 and 66 to drop to their closed position.

35 As will be noted, the dynamic braking circuit extends from terminal 77 of the motor 16, through conductors 76, 105 and 106, contact member 65 of the dynamic braking contactor 36, conductor 115, resistor 38, series field winding 23, conductor 83, contact members 66, conductors 116, 113 and 79 to the terminal 78 of the motor 16.

When the contact members 65 and 66 of the dynamic braking contactor 36 were closed, contact member 67 was opened and the energizing circuit for the operating coil 71 of the main line contactor 37 opened, which entirely disconnects the motor from the line even though the control handle is still maintained in the reverse position.

45 Dynamic braking is thus automatically effected to stop the pusher head in the full open position irrespective of the position of the master controller 41.

55 It is not intended that the invention be restricted to the structural details, circuit connections or arrangement of parts herein shown and described, since it will be readily understood that various modifications there- 60 of may be made without departing from the spirit and scope of my invention.

I claim as my invention:

1. In a rolling mill, in combination, a manipulator pusher head, a motor for actuating the pusher head, a resistor disposed to be

connected in series with the motor, and means responsive to the counter-electromotive force of the motor for connecting the resistor in series with the motor before it is stalled by the stopping of the pusher head.

2. In a rolling mill, in combination, a manipulator pusher head, a motor for actuating the pusher head, a resistor for controlling the current flowing in the motor, switches for short-circuiting the resistor, actuating coils for said switches, said actuating coils being connected across the motor and being responsive to the counter-electromotive force developed by the motor, and adapted to operate the switches upon different voltages to vary the resistance in series with the motor during starting and acceleration and to provide resistance in series with the motor before it is stalled by the jamming of the pusher head.

3. In a rolling mill, in combination, a manipulator pusher head, a motor for actuating the pusher head, said motor having a series field and armature windings, a resistor to control the current flowing in the series field and armature windings, a switch for short-circuiting a portion of the resistor, an actuating coil for said switch, an energizing circuit for the actuating coil, and a plurality of relays having circuit controlling contacts connected in series relation and disposed for controlling the coil energizing circuit, a plurality of operating coils for the relays, said operating coils being connected across the motor armature windings and being responsive to the counter-electromotive force generated by the motor to operate said relays to control the switch coil energizing circuit to vary the resistance in series with the armature and series field windings during the starting and acceleration periods, and to provide resistance in series with the armature and series field windings before the motor is stalled by the jamming of the pusher head.

4. In a rolling mill, in combination, a manipulator pusher head, a motor for actuating the pusher head, said motor having a series field and armature winding, a resistor to control the current flowing in the series field and armature windings, a switch for short-circuiting a portion of the resistor, an actuating coil for said switch, an energizing circuit for the actuating coils and relays connected in series disposed for controlling said energizing circuit, an operating coil for each relay, said operating coils being connected in parallel across the motor armature winding and being responsive to the counter-electromotive forces developed by the motor and adapted to effect the functioning of the relays which control the energizing circuit of the resistor short-circuiting switch, one of said relays being disposed to effect the closure of the short-circuiting switch when a comparatively low counter-electromotive force is developed to accelerate the motor, the other be-

ing responsive to a higher counter-electromotive force to effect the opening of the short-circuiting switch when the motor operates at nearly rated speed and before the motor is stalled by the jamming of the pusher head.

5. In a rolling mill, in combination, a manipulator pusher head, a motor for actuating the pusher head, a resistor for controlling the current flowing in the motor circuit, an electrically-operated switch for short-circuiting a portion of the resistor, a control circuit for the electrically-operated switch, and means responsive to the counter-electromotive force developed by the motor to deenergize the control circuit, before the motor becomes stalled, to connect the desired amount of resistance in series therewith.

6. In a control system for a manipulator pusher head, in combination, a motor for actuating the pusher head, a resistor for governing the speed of the motor, a switch for short-circuiting a portion of the resistor and means responsive to the counter electromotive force developed by the motor to actuate the switch to connect the resistor in series with the motor during the starting period and short-circuit a portion of the resistor during the accelerating period and to connect the resistor in series with the motor when said motor has been accelerated to full speed thereby to limit the inrush of current when the motor is stalled by the jamming of the pusher head.

7. In a rolling mill, in combination, a manipulator pusher head, a motor for actuating the pusher head, a resistor to control the current flowing in the motor, switches for short-circuiting a portion of the resistor, actuating coils for the switches, said actuating coils being connected across the armature of the motor and being responsive to the counter-electromotive force developed by the motor and adapted to operate the switches upon different voltages to vary the resistance in series with the armature during starting and acceleration and to provide resistance in series with the motor armature after it has reached full speed and before it is stalled by the jamming of the pusher head.

50 In testimony whereof, I have hereunto subscribed my name this 3rd day of August, 1927.

PHELAN McSHANE.
